UNITED STATES PATENT OFFICE.

GEORGE WILLIAM HAZLEWOOD, OF BIRMINGHAM, ENGLAND, ASSIGNOR TO WALLS LIMITED, OF BIRMINGHAM, ENGLAND.

SLOW-COMBUSTION HEATING STOVE.

Application filed January 27, 1927, Serial No. 163,998, and in Great Britain November 6, 1926.

This invention relates to slow combustion heating stoves and more particularly is concerned with stoves adapted for the burning of sawdust or like comminuted fuel and wherein in the charging of the fuel into the combustion chamber of fuel container a rod or tube, which may conveniently be termed "a former" is axially arranged in the chamber or container the fuel being rammed or charged into the space between the inner surface of the combustion chamber or fuel receptacle and the rod or tube which rod or tube when the combustion chamber has been charged is withdrawn thereby leaving an air 15 shaft or passage in the mass of fuel and extending vertically therethrough.

The invention consists of a new or improved construction of stove of the kind referred to and is characterized by the arrangement of the combustion chamber or fuel receptacle in an outer casing to which the heated air and products of combustion are conducted from the fuel receptacle or combustion chamber and thence to an outlet flue 25 or conduit.

The invention will be further described with reference to the accompanying drawings.

Figure 1 represents, partly in elevation and partly in vertical section, a slow combustion heating stove constructed in accordance with the invention, the stove being charged with sawdust or like comminuted fuel ready for use.

Figure 2 is a sectional plan of the same, the section being taken on the plane indicated by the dotted line 2—2 Figure 1. The charge of fuel is not indicated in this figure.

Figure 3 is a vertical longitudinal section on the plane indicated by the dotted line 3—3 Figure 2, the "former" being shown in the position which it occupies when the stove is being charged with fuel.

The same numerals of reference indicate the same or corresponding parts in the several figures of the drawings.

In the embodiment of the invention illustrated, 10 is the outer casing of the stove, the said casing being conveniently constituted by a cylindrical body of sheet metal and being supported at its lower end on an end closing plate or base 11 which serves as an ash-pan and which may be fixed to the cylindrical body or it may be detachably connected therewith in the manner hereinafter

more particularly described. The said base plate or ash-pan may be of cast or wrought iron or other suitable metal and be provided, if desired, with feet such as 12 which can be riveted, bolted or otherwise secured thereto. 60

At one side of the outer casing 10 and adjacent the base plate or ash-pan 11 is a cut-away part or aperture 10^a (see Figure 3) adapted to be closed or opened by a door or flap, as for example, the hinged flap 13, the hinge pin 14 of which is mounted on a cast or wrought metal flanged rectangular frame-like member 15 the flange 15^a of which is shaped to fit against the outer casing 10 and may be secured thereto by rivets 16. 70

Or instead of the hinged closing door or flap 13 a sliding closing member may be provided or the closure member may be constructed on the "hit and miss" ventilator principle for the better regulation of the 75 air supply to the stove.

Disposed within the outer casing 10 is a diaphragm 17 which may be of cast or wrought iron or other suitable metal, the said diaphragm having an area proper to closely fit 80 within the outer casing and being fixed or supported therein at a level above the top edge of the air inlet aperture 10^a in the casing 10, the support of the said diaphragm at the requisite height being conveniently 85 effected by the provision on the underside thereof of the legs or props 17^a which rest on the base 11.

The said diaphragm 17 has therein a central aperture 17^b and is provided on its upper face with an upstanding rib or flange 17^c or a series of studs or projections or equivalent means for concentrically positioning within the outer casing a second casing 18 preferably of sheet metal which casing constitutes the combustion chamber proper of the stove and is of such cross sectional dimensions that when positioned in the outer casing 10 an annular space or chamber 19 is left between the presented surfaces of the two 95 casings, the said chamber being hereinafter referred to as the smoke chamber.

The inner casing or combustion chamber 18 extends to the top of the outer casing 10 or into such position relative thereto as will 105 permit its upper end to make contact with a lid or cover by which the upper end of the outer casing is closed. The said cover is preferably constituted by a fixed rim portion 20 which closes the upper end of the smoke 110

chamber 19 and by removable sections 20^a and 20^b which complete the cover the section 20^a being of annular formation and the central section 20^b of a plate or disc-like formation, the rim 20 and sections 20^a and 20^b being furnished with rebated or shouldered peripheries for the engagement and support of the respective parts by each other in a manner well understood.

- 10 The rim section is preferably provided on its underside with incipient flanges or circular ribs 20^c and 20^d which respectively serve to position the upper ends of the tubular outer casing 10 and combustion chamber 18 relative to the rim and the said rim section 20 and base 11 are conveniently connected together with the tubular members 10 and 18 securely clamped and positioned between them by the longitudinal wires or rods 21 which extend through the smoke chamber, the upper ends of the said rods being provided with heads which take a bearing in holes in the rim 20 through which the rods are passed and their lower ends, which pass through holes in the base plate 11 coincident with the holes in the rim 20, being screwed for the reception of screw nuts 22 which on being tightened up on the rods securely brace the parts together.
- 30 This method of connecting or bracing the parts provides for their ready assembly and permits of their being readily disassembled for repair or replacement when necessary or desirable.

- 35 In order to allow the products of combustion to pass from the combustion chamber 18 to the smoke chamber 19 between the same and the outer casing 10 the upper end of the combustion chamber casing is notched or cut 40 away at one or more points to provide a gap such as 18^a through which the said products escape to the annular smoke chamber whence they pass through a side opening 10^b in the outer casing to a flue pipe (not shown) in 45 connection therewith, said opening 10^b to the flue pipe being disposed at or near the lower end of the annular chamber and preferably at the side of the stove opposite to that at which the door regulated aperture 10^a 50 through which air is admitted is located.

For convenience of connection of the stove with a flue pipe I prefer to provide the opening 10^b with a short tubular extension 23 adapted to fit against and be riveted or otherwise fixed on the casing 10, the said extension having combined therewith, if desired, a butterfly valve or pivoted damper plate 24 operable by a projecting rod or handle 24^a or the like.

- 60 For use in conjunction with the stove described when the same is being charged with sawdust or like comminuted fuel I provide a preferably tubular rod 25 the lower end of which is adapted to be fitted temporarily in 65 the central aperture 17^b of the diaphragm 17

which constitutes the bottom of the combustion chamber and to facilitate the positioning operation the lower end of the rod is provided with a wood or other plug 25^a. When the said rod or tube is so arranged it extends 70 axially upwards through the combustion chamber as is illustrated in Figure 3. The upper end of the rod or tube 25 may be provided with a loop or handle to facilitate its manipulation.

75 By employing a tubular rod 25 not only is there a reduction in weight effected but the said tube may serve as a receptacle for the tool 26 which is provided for tamping down the fuel when charging the stove, which can 80 when the tool is not in use, and for convenience of transit or storage, be inserted within the tube as will be understood from an examination of Figure 3 in which figure the tamping tool is indicated in dotted lines, the tool 85 being completely accommodated in the tube, its handle 26^a only projecting therefrom.

When charging the stove the sections 20^a and 20^b of the cover are removed and the rod or tube is arranged in the axis of the combustion chamber as above described. The sawdust or like comminuted fuel marked 27 is introduced from the opened upper end of the combustion chamber and is rammed or tamped down around the rod by the use of 90 the tool 26, until it fills the annular space between the rod and the inner wall surface of the combustion chamber casing. When the combustion chamber has been filled to or near to the upper end thereof the axial rod or tube 95 25 is withdrawn and the fuel is left in the combustion chamber with an axial passage 27^a extending therethrough and in alignment with the aperture 17^b in the base of the combustion chamber which base constitutes 100 the grate of the stove.

105 After charging and removal of the axial rod or tube the upper end of the stove is closed by replacement of the loose section or sections of the lid. Any convenient form of 110 luting may be provided if thought necessary or desirable between the rim 20 and the upper ends of the casings 10 and 18.

The stove is set in operation by the burning of paper or other convenient fuel on the 115 ash-pan 11 below the diaphragm 17 or other convenient means of starting the combustion of the sawdust or the like may be adopted, and when the combustion of the sawdust or the like has been started it will slowly continue to burn so long as air is admitted to the lower end of the stove, until the whole of the sawdust or like block 27 has been burnt, and as hereinbefore stated the products of combustion pass from the combustion chamber 18 to the smoke chamber 19 around the same and thence through the opening 10^b to the flue pipe.

120 The outer casing of the stove is thus very 125 efficiently heated by the products of combus- 130

tion and as the stove is merely consuming waste products the use of stoves in accordance with the invention is attended with a considerable saving in expense.

5 I claim:—

1. A stove for burning sawdust and like comminuted fuel comprising a base, an outer cylindrical sheet metal casing mounted on said base, a side opening provided in said 10 casing adjacent the base, a hinged door for said opening, a horizontal diaphragm fitted within said outer casing and located at a level above the said side opening and spaced from said base, a centrally disposed aperture in 15 said diaphragm, a cover adapted to fit over the upper end of the outer casing, an inner cylindrical tubular sheet metal member concentrically disposed within said outer casing the lower end of the said member abutting 20 the underside of the cover, an annular space between the inner tubular member and the inner surface of the outer casing, an aperture in the upper end of the tubular member for placing the said member in communication 25 with the said annular space, a flue opening formed in the outer casing above the level of the horizontal diaphragm and tie rods adapted to pass through the annular space and to press and hold together the base, outer 30 casing, inner tubular member and cover said tie-rods being wholly concealed from view when the stove is erected.

2. A stove for burning sawdust and like comminuted fuel comprising a base, an outer 35 cylindrical sheet metal casing mounted on said base, a side opening provided in said casing adjacent the base, a rectangular aper-

tured frame riveted to the said outer casing adjacent the side opening therein so that the aperture in the frame coincides with the side 40 opening, a door hingedly connected to the said frame for controlling the passage of air through the side opening, a horizontal diaphragm fitting within said outer casing, and located at a level above the side opening and 45 spaced from said base, a centrally disposed aperture in said diaphragm, a cover adapted to fit over the upper end of the outer casing, an inner cylindrical tubular sheet metal member concentrically disposed within said 50 outer casing the lower end of the said member abutting the underside of the cover, an annular space between the inner tubular member and the inner surface of the outer casing, an aperture in the upper end of the 55 inner tubular member for placing the said member in communication with the said annular space, a flue opening in the outer casing above the level of the horizontal diaphragm and diametrically opposed to the 60 aforesaid side opening in the outer casing, a flanged flue pipe riveted to the outer casing so that it registers with the flue opening, a damper plate pivotally mounted within said flue pipe, an externally disposed handle for controlling said damper plate and tie rods adapted to pass through the annular space and to press and hold together the base, outer 65 casing, inner tubular member and cover said tie rods being wholly concealed from view 70 when the stove is erected.

In testimony whereof, I have signed my name to this specification.

GEORGE W. HAZLEWOOD.
